DESIGN FOR A COMBINATION RECESSED WALL FIXTURE HOLDER FOR SMOKERS' ARTICLES

Chester D. Klauber, New York, N. Y., assignor to The Fairfacts Company, Inc., New York, N. Y., a corporation of New York

Application November 3, 1939, Serial No. 88,024

Term of patent 14 years

To all whom it may concern:

Be it known that I, Chester D. Klauber, a citizen of the United States of America, residing in New York, in the county and State of New York, have invented a new, original, and ornamental Design for a Combination Recessed Wall Fixture Holder for Smokers' Articles, adapted to be recessed into the wall of a room, of which the following is a specification, reference being had to the accompanying drawing, forming part thereof, in which

of Fig. 2, and

Figure 4 is a cross-section on the line 4—4 of
Fig. 2.

I claim:

The ornamental design for a combination recessed wall fixture holder for smokers' articles, substantially as shown.

CHESTER D. KLAUBER.
